Filed Jan. 6, 1970, Ser. No. 20,782
Term of patent 14 years

Int. Cl. D6—01
U.S. Cl. D80—10

FIG. 1 is a front perspective view of a shoe display bracket embodying my new design;

FIG. 2 is a front elevational view thereof;

FIG. 3 is a top plan view thereof;

FIG. 4 is a bottom plan view thereof;

FIG. 5 is a side elevational view thereof, the opposite side being identical; and,

FIG. 6 is a rear elevational view thereof.

The fragmentary broken line representation of a display stand in FIGS. 1, 2, 5 and 6 are for purposes of illustration only.

I claim:

The ornamental design for a shoe display bracket, as shown and described.
